UNITED STATES PATENT OFFICE.

JONAS S. HEARTT AND SAMUEL ENGLISH, OF TROY, NEW YORK, ASSIGNORS
TO JONAS S. HEARTT AND JAMES OSTRANDER, OF SAME PLACE, AND
JOSEPH RIDGWAY, OF SOUTH AMBOY, NEW JERSEY.

IMPROVEMENT IN MACHINES FOR MAKING FIRE-CLAY GAS-RETORTS.

Specification forming part of Letters Patent No. 33,623, dated October 29, 1861.

To all whom it may concern:

Be it known that we, JONAS S. HEARTT and SAMUEL ENGLISH, each of the city of Troy, in the county of Rensselaer and State of New York, have jointly invented a certain new and useful Improved Machine for Making Fire-Clay Gas-Retorts, which invention we have assigned to JAMES OSTRANDER, of the said city of Troy, JONAS S. HEARTT aforesaid, and JOSEPH RIDGWAY, of South Amboy, in the county of Middlesex and State of New Jersey; and we do hereby declare that the following is a full and exact description of our said invention, reference being had to the annexed two sheets of drawings, in which the same letters of reference indicate like parts in all the figures, and the arrows therein point out the directions in which the parts are moved in use.

In the annexed drawings, Figures 1 and 2, Sheet I, are central vertical sections at right angles to each other of one of our improved retort-machines, and Fig. 3 is a partial section of the same, showing a retort in the process of formation. Fig. 4, Sheet II, is a view of the under side of the parts immediately above the line *z z* in Fig. 1, and Fig. 5 is a plan of the parts just below the line *y y* in Fig. 1. Fig. 6 is an isometrical drawing of a retort made by the use of the machine shown by the aforesaid figures; and Fig. 7 is an isometrical drawing of a case, within which the retort is finished by the machine. Figs. 8 and 9 are central vertical sections at right angles to each other of a part of a retort-machine having some of the essential features of that shown by Figs. 1 and 2.

In our improved machine (shown by Figs. 1, 2, 3, 4, 5, and 7 of the annexed drawings,) A is the fixed hollow outer die, and B the fixed core, between which two parts the plastic material X is forced in forming the retort, by means of a feed-screw C, turning in a cylinder D, the end portion of the space between the said core B and die A, Fig. 4, being of the same transverse form and size as a transverse section of the body *w* of the retort. The core B in Fig. 2 does not extend as far as the hollow die A and has an end plate *e*, and the end *v* of the retort is formed by forcing the clay or plastic material into, so as to fill the space

between the end plate *e* and a movable plate F temporarily held at the end of the die A, substantially as shown by Fig. 2. The end plate *e* is separable from the core B, and is secured thereto during the formation of the end *v* of the retort by means of the screw-rod *g*, Fig. 1, or its equivalent, extended through the machine to its outside, so that a person attending the machine can thereby release the plate *e* from the core.

Between the core B and the greater part of its end plate *e* is a space *h*, which by means of a passage *i*, Fig. 1, has communication with the open air or a sufficient supply of air or other suitable fluid, so that after having formed the end *v* of the retort in the manner above described and released the plate *e* from the core B and also liberated the support F, then upon turning the screw C, so as to force the plastic material through the space between the die A and core B, the end *v* of the retort, with the end plate *e*, will freely leave the core, and so that the atmospheric or fluid pressure on the inner and outer surfaces of the retort during its formation will continually be so nearly equal that the retort will not collapse or be crushed inward by the pressure of the atmosphere, while the body of the retort increases in length, and consequently tends to produce a vacuum within itself.

The supporting-platform F is made to recede from the die A as fast as the retort is produced by means of any suitable devices worked either by hand or automatically, as indicated by the annexed drawings. If the die A extended beyond the end of the core B, as shown in Fig. 2, during the formation of the body part *w* of the retort, the plastic material in such a case would be liable to be forced or directed inward by the projecting part of the die A, so as to thereby make the body of the retort defective. To obviate that difficulty and also facilitate the formation of the flange *j* on the retort in the manner hereinafter described without requiring either the whole core B or the end portion of the die A to be movable, we make the core with a shell *k*, Figs. 1, 2, and 3, fitted and arranged so that the shell *k* can be slid longitudinally on the body *l* of the core by means of the screw-rod

g, Fig. 1, or its equivalent, extended through the machine to its outside, so that a person working the machine can thereby retract and hold the shell *k* with its end within the end of the outer die *A*, as shown in Fig. 2, to permit the formation of the end *v* of the retort in the manner above described, and can also release the shell *k*, so that it will extend any required uniform limited distance beyond the die *A*, as shown in Figs. 3 and 1, during the formation of the body of the retort. When the forming-retort becomes extended from the end of the die *A*, as shown in Fig. 3, a distance equal to the length of the completed retort, the revolving feed-screw *C* is stopped and the receding support *F* made stationary. Then to make the flange *j* on the retort, a divisible mold *M*, Fig. 7, open at both ends, and of substantially the same internal form and size as the outside of the finished retort, is placed around the partly-formed retort, as indicated by dotted lines in Fig. 3, the core *B* or its shell *k* being extended within the partly-formed retort and opposite to the recess *n* in the mold *M*. Then the condensing air-pump *P*, Fig. 1, having communication with the interior of the retort by a suitable air-passage *i*, is worked so as to increase the fluid-pressure inside of the retort above the atmospheric pressure, and at the same time the screw *C* is turned so as to force the plastic material into and solidly fill the recess *n* in the mold, and thus form the flange *j* on the retort, as shown in Fig. 1. Then the mold and retort are together slightly withdrawn from the die *A* and the screw *C* stopped, whereupon the retort is severed from the material within the die *A* and removed in and with the mold, the shell *k* being previously retracted within the die *A*, or the mold and retort drawn off together from the core to allow such removal. By thus having the core *B* extend opposite to the recess *n* in the mold while forming the flange *j* on the retort, as above described, the plastic material is prevented from being squeezed into the retort anywhere opposite to the flange, and the increased fluid-pressure made at the same time against the inner surface of the retort straightens and presses the body of the retort hard against the inner surface of the mold *M*, and thereby prevents the retort from being crimped down or bulged inward where not supported by the core *B* or its shell *k*.

Instead of the condensing air-pump *P*, any other suitable apparatus or means having proper communication with the interior of the retort may be used for producing and maintaining a fluid-pressure superior to that of the atmosphere on the inner surface of the retort during the formation of its flange *j* in the manner hereinbefore set forth, and the mold *M*, instead of being divisible, may be so made in one piece and set in the machine at the end of the die *A*, before beginning to form the retort, that the retort will as it is produced enter endwise into the mold, and,

as indicated by the annexed drawings, any suitable devices may be used to sustain, elevate, and lower the supporting-table *F* and the mold *M* in forming the retort; and instead of introducing the air or other fluid into the hollow core *B* and interior of the retort through the hollow spindle *s* of the feed-screw *C*, as shown at *i* in Fig. 1, or by a passage through the core-support *O*, as indicated by dotted lines at *q* in the same figure, the air or its equivalent fluid may be conducted into the hollow core and retort by any other suitably arranged passage, as indicated in Figs. 8 and 9, where the air is admitted through a hollow screw-bolt *r*, extended through the table *F*, end plate *e*, and end *v* of the retort itself, and by the use of which screw-bolt the end plate *e* is in that case secured to and released from the core in forming the end of the retort in the manner hereinbefore described; but we generally prefer the arrangement of air-passage *i* and end-plate fastening *g*, (shown in Fig. 1,) in which case the machine does not leave the retort with a hole through its end; and it is obvious that a piston in a cylinder, or other suitable means, may be employed instead of the screw *C* and cylinder *D* to force the plastic material through the space between the die *A* and core *B* in our improved machine.

We are aware that it is not new to combine or arrange together a hollow die *A*, core *B*, end plate *F*, cylinder *D*, and pressing-piston or feed-screw *C* for use in molding a fire-clay gas-retort with a closed end, but without the flange *j* around its mouth, examples being shown on pages 526 and 527, Vol. 2, Appleton's Dictionary of Machines, &c., New York, 1852, and we do not claim that combination, and we do not broadly claim the admission of air to the interior of a hollow article made with a closed end during its passage from the molding-machine; but we do believe that it is new in machines for molding retorts to make the whole end *e* of the hollow core having communication with the open air freely and entirely removable from the core with and by the action of the end *v* of the retort as the retort begins to pass from the machine, the said end plate *e* being attached to and released from the core substantially as herein represented; and we are aware that it has been heretofore proposed to make the whole core in a machine for molding clay retorts fast to the pressing-piston thereof, so as to move with the piston; but that construction we neither claim nor use, and we do not broadly claim the application of a fluid-pressure greater than that of the atmosphere to the inner surface of hollow plastic articles during their formation within molds.

What we claim as new and of our invention in the above-described machine for making gas-retorts from plastic materials, and desire to have secured by Letters Patent to the aforesaid JAMES OSTRANDER, JONAS S. HEARTT and JOSEPH RIDGWAY, as the assig-

nees of all our right, title, and interest therein, is—

1. The removable plate *e*, when secured to and released from the end of the hollow core *B*, having communication with a supply of atmospheric air or other fluid, as and for the purpose herein set forth.

2. The sliding core-shell *k*, when applied so that the core can be thereby made to terminate either within or beyond the end of the outside die *A*, as herein described.

3. The combination of the condensing air-

pump *P* or any equivalent therefor with the outer die *A*, mold *M*, end support *F*, core *B*, extended opposite to the recess *n* in the mold, and a device for forcing the plastic material between the said core and die into the mold, substantially as and for the purpose herein set forth.

JONAS S. HEARTT.
SAMUEL ENGLISH.
